UNITED STATES PATENT OFFICE.

SIGURD ANDERSON AND LEONARD ANDERSON, OF LEAVENWORTH, KANSAS.

ENVELOP-SEALING MACHINE.

1,247,486.

Specification of Letters Patent. Patented Nov. 20, 1917.

Application filed August 2, 1916. Serial No. 112,703.

To all whom it may concern:

Be it known that we, SIGURD ANDERSON and LEONARD ANDERSON, citizens of the United States, residing at Leavenworth, in 5 the county of Leavenworth and State of Kansas, have invented certain new and useful Improvements in Envelop-Sealing Machines, of which the following is a specification.

10 Our invention relates to improvements in envelop sealing machines, and among the novel features may be mentioned the provision of means whereby envelopes of different sizes can be run through the machine 15 without making adjustments to accommodate such sizes; the provision of means for automatically closing and opening a circuit when electricity is employed as a motive force for operating the machine, to the end 20 that economy in the use of current is obtained as said current is on only when envelopes are passing through the machine; the provision of means for reliably moistening the gummed surfaces of the envelop flaps 25 uniformly, so that said flaps will remain sealed when pressed against the backs of the respective envelopes; the provision of simple and efficient means for folding the moistened flaps toward or against the backs of the 30 respective envelopes, and of means for firmly pressing said moistened flaps against the envelopes to reliably seal the same.

Other features of the invention will hereinafter appear, and in order that said invention may be fully understood, reference 35 will now be made to the accompanying drawings, in which:

Figure 1 is a perspective view of the machine secured to one side of a desk.

40 Fig. 2 is an elevation of the machine with one side of the case removed to disclose the interior mechanism.

Fig. 3 is an irregular vertical section on line III—III of Fig. 2.

45 Fig. 4 is an irregular section on line IV—IV of Fig. 2.

Fig. 5 is a vertical section on line V—V of Fig. 2.

50 Fig. 6 is a fragmental vertical section on the plane of line III—III of Fig. 2.

Fig. 7 is a cross section on line VII—VII of Fig. 5.

Fig. 8 is a plan view of the machine.

55 Fig. 9 is a diagram of an electric circuit employed in carrying out the invention.

Fig. 10 is a vertical section of a fountain

and rollers for moistening the flaps of envelopes.

Referring now to the various parts, 1 designates a suitable case inclosing the mechanism of our machine. Said case is adapted to be hung from the side of a desk A, or other suitable piece of furniture, preferably having space for holding the envelopes to be sealed. By thus hanging the case the machine will not take up valuable space on top of the desk. Said case 1, in the present instance, is divided into compartments 2, 3 and 4, by vertical partitions 5 and 6. The top of the case has a rightangular entrance 60 slot 7 at its upper portion and a delivery slot 8 at its lower portion for the passage of the envelopes. The partition 5 has a vertical slot 9 for the passage of the envelopes B in their travel from the entrance slot 7 to 65 the delivery slot 8. A rightangular guide 10 secured to the top of the case is employed to direct the envelopes into the entrance slot 7 and also hold the flaps C away from the backs of the respective envelopes, so that said 70 flaps cannot prematurely adhere thereto.

The envelopes are advanced through the machine by upper feed rolls 11 and 12, intermediate feed rolls 13 and 14, and a pair of sealing rolls 15 mounted adjacent the 75 bottom of the case 1. The feed rolls 12 and 14 are shorter than their companions to avoid engagement with the rightangular 80 projecting flaps C of the envelopes, and are journaled in suitable ball bearings 16 mounted 85 in the partitions 5 and 6. The long rolls 11, 13 and 15 are journaled in suitable ball bearings 17 mounted in the partition 6 and one of the side walls of the case 1. The partition 5 has openings 18 therein for the passage of the long rolls, as disclosed by Figs. 3 90 and 6.

19 designates a moistening roll arranged at an angle to and adjacent the long feed roll 11 to moisten the gummed side of the 100 flaps C as the envelopes are fed downward through the machine. A pair of guide rolls 20 bend the envelop flaps around a portion of the moistening roll 19 to insure distribution of moisture uniformly over the 105 gummed surfaces. Water or other suitable liquid is supplied to the periphery of the moistening roll 19 by a distributing roll 21, journaled in the lower ends of a pair of rock arms 22, extending down into a fountain 23. The arms 22 are mounted upon pivots 24 projecting from a yoke 25, secured 110

to the upper portion of the partition 5 and constituting a bearing for the moistening roll 19. The upper ends of the rock arms 22 are connected by a transverse rod 26 to which one end of a coil spring 27 is secured. Said spring 27 causes the arms 22 to hold the distributing roll 21 in frictional engagement with the moistening roll 19, so that the latter will drive the former. The 10 opposite end of the spring 27 is attached to the partition 5.

The fountain 23 is supplied from a supply tank 29 secured to the exterior of the case 1, so that it can be readily filled with 15 water. Said supply tank 29 is on substantially the same level as the fountain 23, so that it cannot cause the latter to overflow and possibly short circuit an electric current hereinafter referred to. Water from 20 the supply tank 29 is conducted to the fountain 23 by a pipe 30. The bottom of the supply tank 29 has a drain 31 normally closed by a cap 32. The side of the fountain 23, adjacent the feed roll 11, has a guide 33 to 25 direct the envelops between said feed roll 11 and the adjacent side of the fountain. The moistening roll 19 is positively driven by a fixedly-mounted sheave 34, which in the present instance is driven by an electric 30 motor 35 through the intermediary of sheaves 36 and 37, an endless belt 38, a sheave 39, and an endless belt 40.

The sheave 37, which is considerably 35 larger than the sheave 39, is fixedly-mounted therewith upon a shaft 41 journaled in a pair of bearings 42, depending from the top wall of the case 1. In its passage from the sheave 39 to the sheave 34 the belt 40 runs around a pair of idlers 43, loosely 40 mounted upon a shaft 44 carried by a hanger 45, depending from the top wall of the case 1. The short feed rolls 12 and 14 and one of the sealing rolls 15 are provided with fixedly-mounted sheaves 46, 47 and 48, 45 respectively, driven by an endless belt 49 from a small sheave 50, fixed upon one end of the shaft 41. The sheaves 46, 47 and 48 are of the same diameter to drive their respective rolls at the same speed.

50 The feed rolls 11 and 13, and one of the sealing rolls 15 are driven by frictional engagement with their companions or the intervening envelops, and to this end the bearings of said feed rolls 11 and 13 are arranged 55 in two longitudinal members 51 pressed toward the rolls 12 and 14 by centrally disposed springs 52. Members 51, while free to move backward and forward to accommodate thickly or thinly filled envelops, are 60 held from lateral movement by the adjacent ends of the rolls 11 and 13, and guides 53, which latter are secured to the partition 6. The bearings of the yieldably-mounted sealing roll 15 is journaled in members 54 65 mounted upon pivots 56 carried by arms

56a beneath the members 51, and normally pressed toward the companion roll 15 by springs 57.

As an envelop passes endwise between the feed rolls 13 and 14 its flap contacts a flap 70 folder or deflector 58, secured to the inner side of the adjacent wall of the case 1. Said deflector 58 extends at an angle from the perpendicular to fold the flap against or nearly against the back of the envelop, so 75 that it will be in position to be firmly pressed against said envelop to seal the same, by the sealing rolls 15.

59 designates circuit breakers arranged 80 adjacent the feed rolls, the sealing rolls, and the entrance and discharge slots, as disclosed by Fig. 3. One member 60 of each circuit breaker projects across the slot 9 in order to be raised in contact with the companion member 61 by each envelop in 85 its passage through said slot. The members 60 and 61 are mounted on pivots 62 and 63, respectively, secured to the partition 5, and pivotal movement of the member 61 is restricted by stops 64 projecting from the adjacent side of the partition 5. As disclosed 90 by the diagram, Fig. 9, the members 61 of the circuit breakers are connected in multiple with one another and in series with the motor circuit 65. Hence the motor circuit 95 is closed by the closing of any circuit breaker, and is interrupted only when all of the circuit breakers are open.

In practice the envelops are fed endwise into the slot 7 one by one, the body of each 100 envelop bearing against the long side of said guide. As each envelop is fed downward by hand to the upper feed rolls 11 and 12, it closes the uppermost circuit breaker 59 which in turn closes the circuit 65, thereby 105 starting the motor 35 which in turn drives all of the feed rolls, the sealing rolls, and the moistening roll. As the envelop is seized by the upper feed rolls 11 and 12, it is carried downward thereby to the intermediate rolls 13 and 14, which carry it downward to the sealing rolls 15, which discharge the envelop through the delivery slot 8. As the envelop passes downward the 110 gummed surface of its flap is moistened by the roller 19, then folded against the back of the envelop by the deflector 58, and later firmly pressed against said back by the sealing rolls 15, which cause said gummed surface to firmly adhere to the back of the envelop and thus seal the same. The circuit breakers 59 are spaced a comparatively short distance apart, so that an envelop will 115 contact one before passing entirely out of contact with the circuit breaker above, hence the circuit 65 remains closed until the envelop is discharged through the delivery slot 8, whereupon the circuit 65 is automatically interrupted until closed by the introduction of another envelop through the 120 125 130

entrance slot 7. If desired a continuous stream of envelops may be fed through the machine, but the instant there is an interruption in said stream, the circuit 65 is automatically broken and consequently current is not wasted in running the machine when no envelops are passing therethrough. As the envelops are fed endwise through the machine, the latter will accommodate the 10 smallest to the largest size envelop without requiring adjustment of any of the mechanism.

From the foregoing description it will be readily understood that we have produced 15 an efficient machine embodying the features of advantage above enumerated and while we have shown and described the preferred form of our invention we reserve the right to make such changes in the construction, 20 combination, and arrangement of parts as properly fall within the spirit and scope of the claims.

Having thus described our invention, what we claim and desire to secure by Letters 25 Patent, is:

1. In a machine of the character described, means for advancing envelops, means for applying moisture to the gummed surfaces of the envelop flaps, means for pressing the 30 gummed surfaces of the moistened flaps against the backs of the respective envelops, a motor for driving the envelop advancing means, a circuit for supplying said motor with current, and an automatic circuit breaker actuated by the envelops passing through the machine to close the motor circuit.

2. In a machine of the character described, means for applying moisture to the gummed 40 surfaces of envelop flaps, means for pressing the moistened gummed surfaces of the flaps against the backs of the respective envelops, a motor for driving said pressing means, a circuit for supplying said motor 45 with current, and an automatic circuit breaker actuated to close the motor circuit by the envelops passing through the machine.

3. In a machine of the character described, 50 means for advancing envelops, means for applying moisture to the gummed surfaces of the envelop flaps, means for sealing the envelops, a motor for driving the moisture applying means, a circuit for supplying said 55 motor with current, and automatic circuit breakers actuated to close the motor circuit by the envelops passing through the machine.

4. In a machine of the character described, 60 means for advancing envelops, means for applying moisture to the gummed surfaces of the envelop flaps, means for sealing the envelops, a motor for driving the advancing means, the moisture applying means, 65 and the sealing means, a circuit for supply-

ing said motor with current, and circuit breakers connected in multiple to said circuit and adapted to be actuated to close the motor circuit by the envelops passing through the machine.

5. In an envelop sealing machine, a guide adapted to hold the flaps from the bodies of the envelops, two feed rolls adjacent said guide to advance the envelops, one of said rolls being shorter than the other to avoid 70 touching the envelop flaps, a moistening roll adjacent the longer feed roll to moisten the gummed surface of the flaps and assist in advancing the envelops, and a pair of guide rolls to guide the flaps against the surface 75 of said moistening roll.

6. In an envelop sealing machine, a guide at one end of the machine adapted to hold the flaps from the bodies of the envelops, feed rolls adjacent said guide to advance the 80 envelops, one of said rolls being shorter than the other to avoid touching the flaps, a moistening roll adjacent the longer feed roll to moisten the gummed surface of the flaps, means to press the flaps against the surface 85 of said moistening roll, a font, and a distributing roll in said font for applying a liquid to the moistening roll.

7. In an envelop sealing machine, a vertically arranged case, an angular guide and 90 an entrance slot at the top of said case adapted to hold the flaps from the bodies of the envelops as they are fed into the machine, two feed rolls adjacent said guide to advance the envelops, one of said rolls being 95 shorter than the other to avoid touching the envelop flaps, a moistening roll adjacent to and set at an angle to the longer feed roll to moisten the gummed surface of the flaps, means below the moistening roll for folding 100 the flaps against the bodies of the envelops, and sealing rolls for sealing the envelops and discharging them through a slot in the bottom of the machine.

8. In an envelop sealing machine, a guide 110 at the entrance to the machine adapted to hold the flaps from the bodies of the envelops, means for moistening the gummed surface of the flaps, feed rolls to advance the envelops, one of said feed rolls being shorter 115 than the other to avoid touching the envelop flaps, two sealing rolls for sealing the envelops, and a rigid inclined deflector extending from a point adjacent the long feed roll to a point adjacent the contacting surfaces of the sealing rolls and arranged in the path of the flaps to direct them toward the backs of the envelops and between said sealing rolls.

9. In an envelop sealing machine, feed 125 rolls for advancing the envelops, a motor for driving said feed rolls, a circuit for supplying said motor with current, a circuit breaker member connected to one side of said circuit, and a second circuit breaker member con- 130

- neeted to the opposite side of the circuit to normally interrupt the same and arranged in the path of the envelops to be actuated thereby to close the circuit and stop the motor.
- 5 10. In an envelop sealing machine, means for moistening the gummed surface of the envelop flaps, feed rolls for advancing the envelops, sealing rolls for sealing the envelops, a motor for driving said feed rolls and the sealing rolls, a circuit for supplying said motor with current, circuit breaker members spaced apart and connected to one side of said circuit, and other circuit breaker

members connected to the opposite side of the circuit to normally interrupt the same 15 and arranged in the path of the envelops to be actuated thereby to close the circuit and start the motor.

In testimony whereof we affix our signatures, in the presence of two witnesses.

SIGURD ANDERSON.
LEONARD ANDERSON.
